APPAREL GARMENT

Benn Lewis, Maplewood, N. J., assignor to Lewel Mfg. Co., Inc., New York, N. Y., a corporation of New York

Application January 17, 1938, Serial No. 185,359

6 Claims. (Cl. 2-37)

This invention relates generally to apparel for feminine wear. More particularly, my invention relates to an improved construction for girdles, corsets and the like.

- 5 One of the objects of my invention is to provide a girdle or corset construction of the character described having novel and improved means associated with the front of said girdle for resiliently confining or compressing the abdomen. 10 Another object of my invention is to provide a girdle or corset construction of the character described, having improved means associated with a double-walled back thereof whereby to prevent relative slipping of the said back portions 15 of the corset when the same is worn.

Still another object of my invention is to provide an improved girdle or corset construction of the character described which shall comprise relatively few and simple parts, which shall be 20 easy to assemble, which shall be relatively inexpensive to manufacture, which shall be rugged in construction and yet neat in appearance, and which, at the same time, shall possess a high degree of efficiency for the purposes intended.

25 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible embodiments 35 of this invention,

Fig. 1 is a front elevational view of a girdle embodying my invention.

Fig. 2 is an enlarged view thereof with the girdle turned inside out disclosing the inner construction of the front thereof.

Fig. 3 is a perspective view of the girdle shown in Fig. 1 but illustrating the rear elevational view thereof as worn on the figure.

45 Fig. 4 is an enlarged view of the girdle illustrated in Fig. 3 but turned inside out to disclose the inner construction of the back of said girdle.

Fig. 5 is an enlarged cross-sectional view taken substantially on the line 5-5 of Fig. 1.

50 Fig. 6 is a view similar to Fig. 2 but showing my invention as applied to the construction of a corset or foundation garment.

Fig. 7 is a view similar to Fig. 4, but illustrating my invention as applied to the corset or foundation garment of Fig. 6; and

Fig. 8 is a front elevational view of the corset or foundation garment shown in Figs. 6 and 7.

Referring now in detail to the drawings, and particularly to Figs. 1-5 thereof, I have disclosed a girdle adapted to be used for feminine wear as 5 a compression or confining garment and constructed in accordance with my invention. The girdle comprises a front portion 10, a back portion 11, and two interconnecting side portions 12 and 13. The side portions 12 and 13 may be 10 made of elastic material, stretchable in a horizontal direction. The girdle may be provided with a slit, extending downwardly from the top edge thereof, suitably disposed and provided with a series of hookless fastener elements 10a and an 15 operating slider 10b as shown in Fig. 1 of the drawings.

The front portion 10 is preferably constructed of a panel 14 which is of triangular shape and having the base thereof continuous with the top edge 15 of the girdle. On opposite sides of the panel 14 are a pair of panels 16 which are symmetrical in shape and each of which has one edge 17 thereof coinciding with a portion of one of the legs of the triangular panel 14 and another edge 18 thereof of arcuate shape. The top edges of the panels 16 are continuous with the top edge 15 of the girdle while edges 19 thereof are fastened along the junction of the side portions 12 and 13 and the front portion 10. The remainder 20 of the front portion 10 comprises a pair of symmetrical panels 20 disposed on opposite sides of a panel 21. The panel 21 may have a triangular portion thereof cut out and fitted with an elastic gusset 22 as shown. The panel 14, and the panels 16, are preferably made of elastic material 25 while the panel 21 and the panels 20 are of inelastic material.

It is thus seen from the above described construction, that the material adjacent the top of the front portion 10 will be resilient and stretchable in a horizontal direction and relatively rigid in a vertical direction, while the remainder of the front portion 10 will be non-stretchable or inelastic with the exception of the bottom gusset 22. The central panel 14 and the side panels 16 may be interconnected by the seams 23 and 24, while the panels 20 may be interconnected with the panel 21 by means of the seams 25 and 26. The seams 27 serve to interconnect the elastic panels 16 to the inelastic panels 20 while the seams 28 serve to interconnect the elastic panels 16 with the inelastic panel 21.

In Fig. 2 there is shown in enlarged form the girdle illustrated in Fig. 1 and which has been 30 35 40 45 50 55 60 65 70 75 80 85 90 95

turned inside out to disclose the inner construction thereof, which comprises panel member 30 of inelastic, non-stretchable material overlying the inside surface of the front portion 10. The member 30 may have a portion 31 of each of the side edges thereof permanently attached at the junction of the side portions 12 and 13 and the front portion 10. The remaining portions 31a of the side edges of the member 30 are curved as shown, to provide a reduced and slightly tapered lower portion of the member 30. The bottom edge 32 of the member 30 is permanently attached to the band 33 disposed adjacent the bottom edge of the girdle. A relatively small portion 34 of the top edge 35 of the member 30 may be permanently attached to the band 36 disposed adjacent the top edge of the girdle. A portion 37 adjacent the lower edge of the member 30 may be cut out, said portion 37 being of the same size and in registered relationship with the cut out portion at the bottom of the front 10 of the girdle so that the gusset 22 may be permanently attached to the member 30 by the lines of stitches 38 and 39, as well as to the front portion panel 21. It is thus seen from the above described construction that the member 30 is confined or permanently attached to the front portion 10 of the girdle by the seams 31, 32, 34, 38 and 39, leaving the edges 35 and 31a free and unconfined.

The member 30 is provided with a plurality of reinforcing stays 40 substantially vertically disposed and extending downwardly from the top edge of the girdle, a pre-determined distance. The stays 40 may be confined within the pockets 41 constructed in the customary manner. The bands 33 and 36 may be made of elastic material.

It is now seen that in donning the girdle, the outer wall of the front portion 10 thereof will be permitted to stretch in a horizontal direction in order to accommodate itself to the figure of the wearer to a certain extent. The amount of horizontal stretching, due to the construction of the panel 14 and the panels 16, will be limited on account of the inner inelastic wall member 30 which is permanently attached to the front portion at the seams 31. When the limit of the horizontal stretching of the front portion has been reached, the tendency will be for the member 30, and the reinforcing stays 40 mounted therein to press inwardly to compress the abdomen.

In Figs. 3 and 4 I have shown the construction of the back portion 11 of the girdle. In Fig. 3 it is seen that the back portion 11 comprises a single panel, with the exception of the small triangular portions 45, of elastic material which is stretchable in a vertical direction and substantially inelastic in a horizontal direction.

In Fig. 4 I have shown the girdle illustrated in Fig. 3 but turned inside out to disclose the inner construction of the back portion 11 thereof. Overlying the back portion 11 is an inner back wall member 50 of inelastic nonstretchable material, substantially of the same size and shape as the back portion 11 and which has the opposed vertical edges 51 and 52 thereof, permanently attached to the back portion 11 adjacent the junction of the side portions 12 and 13 with the said back portion 11. Portions of the corners of the member 50, adjacent the top edge 53 thereof, are cut away and permanently attached to the back portion 11 by means of rows of stitching 54, while the top edge 53 is permanently attached to the upper band 36. It is noted that the bottom edge 55 of the member 50 is slightly shorter than the

back portion 11 and is entirely free and unconfined. The member 50 may be provided with stays 56 which are vertically disposed and which extend substantially the entire vertical height of the member 50. The stays are held in suitable pockets 57.

To present relative sliding or slipping displacement of the inner wall member 50 and the back portion 11 when the girdle is worn, which is unsightly and causes discomfort to the wearer, I have provided the following novel garter construction which prevents this relative movement between the member 50 and the portion 11. One of the ends 60a of each of the elastic loops 60 is permanently attached to the bottom free edge 55 of the member 50, while the other end 60b of the loop 60 is permanently attached to the bottom edge of the back portion 11 of the girdle. Carried by the loops 60 are garter fastener devices 61 of usual construction, designed to grasp the upper edge of the stocking in the customary manner.

It is thus seen from the above described construction that when for any reason a downward pulling strain is exerted against the elastic loops 60, the said strain will be substantially equally divided between the member 50 and back portion 11 of the girdle so that there will be no relative movement between the said parts 50 and 11 when the wearer of the girdle bends or moves in any manner which heretofore tended to cause the inner wall member 50 to move upwardly and cause wrinkling and annoyance to the wearer.

In Figs. 6 and 7, I have shown my invention as applied to a corset or foundation garment. It is noted that as in the case of the girdle construction above described, the front portion 10' of the foundation garment (see Fig. 8) is provided with a centrally disposed elastic panel 14' and a pair of elastic panels 16' disposed on either side of the panel 14' and attached thereto substantially in the same manner as described in connection with the girdle construction. Attached to the upper edges of the panels 14' and 16' are a pair of brassière members 70 of any suitable material such as lace, and constructed in the usual manner. The brassière sections 70 are provided with shoulder straps 71, one end of which is fastened to the upper portion of the brassière, as shown, while the other end thereof is attached to the top edge 35' of the back portion 11' of the foundation garment. The remainder of the front portion of the foundation garment is constructed of inelastic panels similar to the panel 21 and the panels 20 and a bottom triangular elastic gusset 22' is provided, similar to the gusset 22. In Fig. 6 the foundation garment is shown as turned inside out, and it is noted that the inner construction thereof is similar to the inner front portion construction of the girdle, as shown in Fig. 2 of the drawings. An inelastic member 30' is designed similar to that of the member 30. The member 30' is permanently attached to the front portion 10' of the foundation garment in the same manner as the member 30 is attached to the front portion 10 of the girdle with the exception of the stitching at 34, as shown in Fig. 2, connecting the upper edge of the member 30' to the front portion 10'. In the Fig. 6 form of garment, the upper edge 35' of the member 30' is entirely free and unconfined. A plurality of vertically disposed stays 40' are provided, similar to the stays 40.

The back portion 11' of the foundation garment is constructed in a similar manner to that of the back portion 11 of the girdle. In Fig. 7, the

foundation garment is shown turned inside out similar to the girdle shown in Fig. 4. It is seen that a member 59' is provided which is similar in construction and function to the member 59 of the girdle as clearly illustrated in Fig. 4 of the drawings.

It is understood from the above described construction that my invention may be satisfactorily applied to any other similar types of corsets or constricting garments adapted for feminine wear.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In a construction for corsets, girdles and the like, a front portion, a back portion and side portions interconnecting said front and back portions, said front portion comprising a central elastic panel in the upper half thereof a pair of elastic panels symmetrically disposed on opposite sides of said central panel and connected directly thereto, and a member entirely inelastic overlying the inner wall of said back portion, said inelastic member having the top and side edges thereof fixed to said back portion, leaving the bottom edge thereof free and unattached.

2. In a construction for corsets, girdles and the like, a front portion comprising a centrally disposed triangular shaped elastic panel and a pair of elastic panels symmetrically disposed on opposite sides of said central panel and connected directly thereto, a back portion and side portions interconnecting said front and back portions, a member made entirely of inelastic material overlying the inner wall of said back portion, said inelastic member having the top and side edges thereof fixed to said back portion, leaving the bottom edge thereof free and unattached, garter loops, each of said garter loops having one end thereof fixed to said inelastic member, and the other end thereof fixed to said back portion for the purposes set forth, and stays carried by said inelastic member.

3. In a construction for corsets, girdles and the like, a front portion, a back portion and side portions interconnecting said front and back portions, said front portion comprising a V-shaped elastic panel in the upper half thereof, a pair of elastic panels symmetrically disposed on opposite sides of said central panel and connected directly thereto, inelastic panels connected directly to said elastic panels, an inelastic member overlying the inner wall of said front portion, the upper part of

said inelastic member being substantially equal in width to the width of the upper part of said front portion, said inelastic member having portions of the bottom and side edges thereof fixed to said front portion, leaving other portions of said side edges free and unattached, and stays carried by said inelastic member, and a second inelastic member overlying the inner wall of said back portion, said second inelastic member having the top and side edges thereof fixed to said back portion, leaving the bottom edge thereof free and unattached.

4. In a construction for corsets, girdles and the like, a front portion, a back portion and side portions interconnecting said front and back portions, said front portion comprising a centrally disposed elastic panel in the upper half thereof, a pair of elastic panels symmetrically disposed on opposite sides of said central panel and connected directly thereto, inelastic panels connected directly to said elastic panels, a pair of elastic panels disposed on opposite sides of said central panel and connected thereto, an inelastic member overlying the inner wall of said front portion, said inelastic member having the bottom edge thereof and portions of the side edges thereof permanently attached to said front portion, other portions of said side edges remaining unattached, a second inelastic member overlying the inner wall of said back portion, and having the top and side edges thereof fixed to said back portion, leaving the bottom edge thereof free and unattached, and garter loops, each of said loops having one end thereof fixed to said second inelastic member, and the other end thereof fixed to said back portion for the purposes set forth.

5. In a construction for corsets, girdles and the like, a front portion, a back portion and side portions interconnecting said front and back portions, said front portion comprising a centrally disposed V-shaped elastic panel in the upper half thereof, and a pair of elastic panels disposed on opposite sides of said central panel and connected thereto, said last named pair of panels having V-shaped portions at the lower ends thereof and a pair of brassière sections attached to the upper edge of said elastic panels.

6. In a construction for corsets, girdles and the like, a front portion, a back portion and side portions interconnecting said front and back portions, said front portion comprising a centrally disposed triangular-shaped elastic panel in the upper half thereof, a pair of elastic panels disposed on opposite sides of said central panel and connected thereto, and inelastic panels connected to said elastic panels and to each other, and a triangular shaped elastic gusset adjacent the bottom edge of said front portion, the apices of said gusset and said central panel being arranged in opposed relationship.

BENN LEWIS.
